CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,396,739.

Specification of Letters Patent. Patented Nov. 15, 1921.

Application filed September 30, 1920. Serial No. 413,834.

To all whom it may concern:

Be it known that I, CLARENCE B. FOWLER, a citizen of the United States, residing at New York city, in the county of New York and State of New York, have invented certain new and useful Improvements in Telephone-Exchange Systems, of which the following is a full, clear, concise, and exact description.

10 This invention relates to telephone exchange systems and particularly to systems of this nature in which common battery and local battery telephone lines terminate at a central office.

15 In such systems it is often necessary to extend a call received over a local battery line either to another local battery line or to a common battery line, by means of an operator's link or cord circuit.

20 In interconnections of this nature it is desirable that the operator receive suitable supervisory signals to indicate that either of the connected parties is signaling for a disconnection as well as to indicate the character 25 of the line circuit over which the party called is signaling. It is also of advantage in systems of this kind to provide means whereby the subscriber whose station is connected to a common battery line may 30 be enabled to recall the operator at the central office in some distinctive manner.

The object of the present invention is to provide an improved signaling means for telephone systems of this character in which 35 various desirable supervisory signals are produced in a positive manner without requiring signaling devices additional to those required by the ordinary link circuit used for interconnecting lines of a similar character.

40 In order to attain this object in accordance with one feature of this invention there is provided a so-called semi-universal link circuit which is provided with supervisory signaling devices associated with each end thereof and with means which causes the individual or cooperative functioning of these devices in response to the signals received from the local battery or common battery 45 lines, so as to provide distinctive disconnect signals for either character of lines, as well as to provide a distinctive recall signal for the common battery line, which is effective in the absence of a signal from 50 the calling local battery line.

The invention will be more clearly understood from the following description thereof and the accompanying drawing, the figure of which shows one embodiment of the invention.

60 Referring to the drawing, a local battery line circuit A terminates in a jack 10 and an associated signaling device 11 before an operator at whose position there may be provided a plurality of link circuits, D, 65 adapted to extend a call from the line circuit A to a local battery line circuit B, or to a common battery line circuit C. A supervisory lamp 20 associated with the answering plug 15 of the link circuit is adapted 70 to be intermittently operated at a steady rate upon receiving a disconnect signal from the subscriber on the line circuit A, as well as upon a similar signal from the subscriber on the line circuit B if the calling plug of 75 the link circuit is connected with the latter line. The supervisory lamp 30 associated with the calling plug of the link circuit is adapted to be steadily illuminated in response to a disconnect signal from the subscriber on the line circuit B when so connected to the link circuit D. Lamp 30 is also adapted to be steadily illuminated on a disconnect signal from the subscriber on line C, and intermittently illuminated on a recall signal from the same subscriber. If, however, the subscriber of line A signals before the subscriber of line C, then the lamp 30 will be intermittently illuminated by 80 either a recall or disconnect signal from the subscriber of line C.

85 It is thought that the invention may be more fully comprehended from the following description of the operation of the circuits shown in the drawing. The subscriber 90 at the station on the line circuit A, desiring to signal the operator at the central office, actuates the hand generator at such station, which causes the operation of the drop or other signaling device 11. The operator, observing the signal inserts the plug 15 of one of a plurality of cord circuits D located at her position, into the jack 10. The signaling device 11 is thereby rendered ineffective due to the opening of the normally 100 closed contacts of jack 10. Relay 23 thereupon operates over a circuit extending from battery through the left-hand winding of relay 23, the sleeve contacts of plug 15 and jack 10, and the resistance 12 to ground. 105 110

The operator thereupon actuates the listening key 31, which connects the usual operator's telephone set (not shown) with the operator's cord circuit D. Upon ascertaining that the calling subscriber desires to converse with the subscriber whose station is connected with the line circuit B, the listening key 31 is restored to normal and the calling plug 33 is inserted into the jack 40. 10 The opening of the local normal contacts of jack 40 disconnects the winding of the signaling device 41 from the conductors of the line circuit B. A circuit is also completed, extending from battery through the right-hand winding of relay 23, the winding of marginal relay 26, the sleeve contacts of plug 33 and jack 40, and the high resistance 42 to ground. Due to the high resistance 42, marginal relay 26 receives insufficient current for its operation. Therefore, both windings of relay 27, in series, remain in bridge relation across the talking conductors of the calling end of the cord circuit. 15 Upon the completion of the conversation, if the subscriber whose station is associated with the line circuit A desires to transmit a disconnect signal to the operator the actuation of the hand generator at such station causes the flow of alternating current from the hand generator over a circuit including the tip and ring contacts of jack 10 and plug 15, the normal contacts of ringing key 21, and the right-hand winding of relay 22. In 20 response to the current flowing from the hand generator, supervisory relay 22 operates, and locks over a circuit, extending from battery through the contact of relay 23, the local contact of listening key 31, and the left-hand winding and left-hand contact of relay 22 to ground. A circuit is completed by the closure of the right-hand contact of relay 22, which extends from battery through the winding of relay 16, the resistance 19, the lamp 20, and the right-hand contact of relay 22 to ground. Lamp 20 is thereupon illuminated and relay 16 is 25 operated. However, immediately upon the operation of relay 16, a branch path is produced, which may be traced from ground through the interrupter 17, the right-hand contact of relay 16, and the resistance 18 to the upper terminal of resistance 19, where it joins the previously traced path. Lamp 20 is thereby flashed at a constant rate determined by the speed of rotation of the interrupter 17. The flashing of lamp 20 indicates to the operator that the subscriber 30 whose station is connected with line A desires to terminate the connection. However, the operator challenges the signal by actuating the listening key to ascertain positively from the subscriber whether a disconnection is desired. The actuation of the lis-

tening key 31 causes the release of relay 22, the opening of the circuit of relay 16 and the lamp 20 which thereupon ceases to flash.

In case the subscriber whose station is on the line circuit B desires to signal the operator, the actuation of the hand generator thereat causes the flow of ringing current over a circuit which includes the line conductors, the tip and ring contacts of jack 40 and plug 33, the normal contacts of ringing key 32, the right-hand normal contact of relay 26, and both windings of relay 27 in series. The response of ringing response relay 27 causes the operation of relay 24 over a circuit extending from battery through the contact of relay 23, the normal contact of listening key 31, the winding of relay 24, the normal contact of relay 25, the alternate contact of relay 27, the resistance 28, and the lamp 30 to ground. Relay 24, in operating 75 locks over a circuit, including the middle contact thereof and in closing such middle contact, relay 24 shunts the lamp 30 over a path extending from ground through the middle contact of relay 24, and normal contact of relay 25, the alternate contact of relay 27 and the resistance 28 to the terminal of lamp 30. The lamp 30 is therefore prevented from being lighted under this condition. However, as soon as the flow of 80 ringing current from the hand generator of the line circuit B ceases, and the relay 27 releases, lamp 30 is illuminated through a circuit which may be traced from battery through the right-hand winding of relay 25, 85 left-hand contact of relay 24, normal contact of relay 27, resistance 28, and lamp 30 to ground. Relay 25 operates and locks up from battery through its left-hand winding and contact and the right-hand contact of 90 relay 24 to ground. The closure of the right-hand contact of relay 24 completes a circuit which extends from battery through the winding of relay 16, the resistance 19, the lamp 20, the left-hand normal contact of relay 26 and the right-hand contact of relay 24 to ground. Relay 16 immediately operates and completes a shunt path including the interrupter 17, in the manner previously 95 described, so that lamp 20 flashes at a constant rate as in the case of the disconnect signal being received from the subscriber whose station is connected with the line circuit A. Thus, as a result of the disconnect signal received over the local battery called line circuit, lamp 30 is steadily illuminated and lamp 20 flashes constantly. The operator may thereupon challenge the signal, as in the previous case, by actuating listening key 31, and upon ascertaining that the called party 100 desires to have the line disconnected from the cord circuit, both plugs 15 and 33 are removed from the associated jacks and all apparatus is restored to normal.

In case the operator in answering a call re- 105

ceived over the line circuit A, as previously described, ascertains that connection is desired with the common battery subscriber's line circuit C, the plug 33 is inserted into jack 50. The line relay 51 is disconnected from operative association with the line conductors by the opening of the normally closed local contacts of the jack 50, thereby preventing the illumination of the usual line lamp 53. The resistance 52 is of a comparatively low value so that marginal relay 26 now operates over a circuit extending from battery through the right-hand winding of relay 23, the winding of relay 26, the sleeve contacts of plug 33 and jack 50, and the resistance 52 to ground. The opening of the right-hand normal contact of relay 26 removes the serially interconnected windings of relay 27 from the bridge relation across the talking conductors of the calling end of the cord circuit D, while the closure of the left-hand inner and right-hand outer alternate contacts of relay 26 connects ground and battery, at these contacts, respectively, through the left-hand winding of relay 27 to the line conductors. A circuit is closed through lamp 30 which is illuminated, which circuit may be traced from battery through the right-hand winding of relay 25, which operates, the right-hand, inner contact of relay 26, normal contact of relay 27, resistance 28 and lamp 30 to ground. The operator may then actuate the ringing key 32, causing ringing current to flow from the source through the lower alternate contact of key 32, the ring contacts of plug 33 and jack 50, the signaling bell at the station on the line circuit C, the tip contacts of jack 50 and plug 33, and the upper alternate contact of key 32 to ground. The called subscriber, in responding to the signal produced by the ringer removes the receiver from the switchhook, completing the line circuit so that relay 27 is operated over a circuit extending from battery through the right-hand outer alternate contact of relay 26, the left-hand winding of relay 27, the lower normal contact of ringing key 32, the ring contacts of plug 33 and jack 50, the telephone apparatus at the station on the line circuit C, the tip contacts of jack 50 and plug 33, the upper normal contact of ringing key 32, and the left-hand inner alternate contact of relay 26 to ground. In operating, relay 27 opens the circuit previously traced through lamp 30 and the right-hand winding of relay 25. Lamp 30 is extinguished and relay 25 releases. Relay 27 also completes a circuit extending from battery through the contact of relay 23, the local normal contact of listening key 31, the winding of relay 24, the normal contact of relay 25, the alternate contact of relay 27, the resistance 28, and the lamp 30 to ground. Relay 24 immediately operates and locks over the circuit previously mentioned

therefor, and in closing its right-hand contact, shunts the lamp 30 by the resistance 28, thereby preventing the illumination of such lamp.

Upon the completion of the conversation, if the called party desires to signal the operator for a disconnection, the receiver is placed on the hook, thus opening the line circuit and allowing relay 27 to release. A circuit may then be traced from battery through the right-hand winding of relay 25, the left-hand contact of relay 24, the normal contact of relay 27, the resistance 28, and the lamp 30 to ground. Relay 25 thereupon locks through its left-hand winding so that the lamp 30 is steadily illuminated over a circuit which includes the right-hand winding of relay 25.

Upon observing the steadily illuminated condition of lamp 30, the operator may remove the plug 33 from the jack 50, and upon ascertaining that the subscriber, whose line is connected with the answering end of the cord circuit, has completed the conversation, the latter-mentioned plug may also be removed and all apparatus restored to normal.

In case the subscriber on the common battery line circuit C desires to recall the operator, to indicate that another call is desired to be extended or that the other connected party should be recalled, the subscriber may remove the receiver from the switchhook, causing the re-operation of relay 27 over the circuit previously traced therefor, so that relay 16 is now connected in circuit with the lamp 30 over a path extending from battery through the winding of relay 16, the right-hand alternate contact of relay 25, the alternate contact of relay 27, the resistance 28, and the lamp 30 to ground. Immediately upon the operation of relay 16, a circuit is also formed which extends from ground through the interrupter 17, the left-hand alternate contact of relay 16, the left-hand alternate contact of relay 26 and resistance 29 to the terminal of the lamp 30. Therefore, as long as the subscriber's receiver remains off the hook, the lamp 30 will flash at a predetermined rate until the operator actuates the listening key 31. The actuation of listening key 31 to ascertain the needs of the subscriber signaling the operator, opens the locking circuit of relay 24 which, in releasing, releases relay 25, and thereby disconnects the relay 16 from its relation with the lamp 30. If, however, the subscriber of the calling local battery line at this time also signals for a disconnection, both lamps will flash intermittently, lamp 20, as previously described, and lamp 30, by reason of the shunt path which may be traced from ground through the interrupter 17, left-hand alternate contacts of relays 16 and 26 and resistance 29

to the upper terminal of lamp 30. This will indicate to the operator that the subscribers of both lines have signaled and that the called line is of the common battery type.

5. Thus it may be seen that with the two supervisory signaling devices becoming associated with either end of the cord circuit, a disconnect signal from the calling local battery line produces a flashing of the associated answering lamp while a similar disconnect signal from a called local battery line produces a similar flashing of the same lamp and the steady illumination of the supervisory lamp associated with the calling end of the cord circuit.
- 10

When there is no signal from the calling subscriber's line, the disconnect signal, being transmitted from the common battery line circuit connected with the calling end 20 of the cord circuit, causes the steady illumination of the lamp associated with such end, and upon a recall from such a line circuit, the lamp is caused to flash in a manner similar to that of the lamp at the other end 25 upon a disconnect signal being received from a local battery line. If, however, the calling subscriber has previously signaled, then, as explained above, both lamps will flash intermittently upon either a disconnect or a 30 recall signal from the called common battery line.

What is claimed is:

1. In a telephone exchange system, telephone lines of various characteristics, a link 35 circuit for interconnecting the lines, an answering supervisory signaling device controlled over one character of called line, a calling supervisory signaling device controlled over each character of called line and 40 means to cause said answering and calling supervisory signaling devices to indicate by their joint action the character of a called line signaling for a disconnection.

2. In a telephone exchange system, common battery and local battery telephone 45 lines, a link circuit for interconnecting the lines, an answering supervisory signaling

device controlled over a called local battery line, a calling supervisory signaling device controlled over a called line of either character, said signaling devices indicating by 50 their joint action the character of a called line signaling for a disconnection.

3. In a telephone exchange system, common battery and local battery telephone 55 lines, a link circuit for interconnecting the lines, an answering supervisory signaling device controlled over a called local battery line, and a calling supervisory signaling device, said calling supervisory signaling device 60 indicating on a signal from a called line, when said signaling device alone is displayed, the character of the line and the nature of the signal.

4. In a telephone exchange system, common battery and local battery telephone 65 lines, a link circuit for interconnecting the lines, an answering supervisory signaling device controlled over a called local battery line, a calling supervisory signaling device controlled over a called line of either character, 70 said signaling devices coöperating on a signal from a called line to indicate the character of the line.

5. In a telephone exchange system, common battery and local battery telephone 75 lines, a link circuit for interconnecting the lines, an answering supervisory signaling device controlled over a called local battery line, a relay associated with the calling end 80 of said link circuit responsive to current over the called line, and means responsive to the actuation of said relay and to the connection of the calling end of the link circuit with the local battery line to cause 85 the display of said answering supervisory signaling device when the calling end of said link circuit is connected with a local battery line.

In witness whereof, I hereunto subscribe 90 my name this 27th day of September, A. D. 1920.

CLARENCE B. FOWLER.
